UNITED STATES PATENT OFFICE.

MARY McCABE AND WILLIAM J. McCABE, OF NEW YORK, N. Y.

ATTACHMENT FOR SEWING-MACHINES.

1,148,178.

Specification of Letters Patent. Patented July 27, 1915.

Application filed May 16, 1914. Serial No. 839,119.

To all whom it may concern:

Be it known that we, MARY McCABE and WILLIAM J. McCABE, citizens of the United States, residing at New York, in the county 5 of New York and State of New York, have invented certain new and useful Improvements in Attachments for Sewing-Machines; and we do hereby declare the following to be a full, clear, and exact description of the 10 invention, such as will enable others skilled in the art to which it appertains to make and use the same.

Our invention relates to attachments for sewing machines and in particular to a foldable support for sewing machines.

An object of our invention is to give a foldable support having two upright standards in parallel position to each other and carrying the driving gear therefor.

Another object of our invention is to so 20 arrange the folded parts that when folded, they will be as compact and close fitting as it is possible to arrange them.

With these and other objects in view to be 25 developed as we proceed with our specification, we shall proceed to explain the same in which similar characters of reference refer to similar parts in the drawings, and in which a preferred embodiment is shown 30 therein.

Figure 1 of the drawings is an elevational view of our device in open or operable position. Fig. 2, a top plan view of the table a portion of our device. Fig. 3, a top plan 35 view of our treadle in assembled position. Fig. 4, a side view of our device in open position in carrying the driving mechanism. Fig. 5 is a side view of the opposite side of our device to that shown in Fig. 4.

In Fig. 1 of the drawings, 1 is the base member to our foldable side which carries the driving mechanism, consisting of the treadle wheel 3, driving pitman 4 and treadle 5, and the skirt protector 2.

The treadle can be of any preferred structure but in the preferred embodiment as shown in Fig. 3 of the drawings it consists of an open framework 6, having closed-in portions 7 and 8 to act as a foot rest for the 45 toe and heel portions of the foot. The frame 6 is mounted for oscillatory action on the shaft 9, and has at one end thereof, an extension 10 to which is attached our pitman connection 11, the driving pitman 4 being 55 pivotally connected to the same. Pivotally connected as at 12 to the upper portion of

our base member 1 is a foldable section 13, said section having a hinged connection 14 at the upper exterior corner thereof, and an inward projecting lug 15 on the inner 60 surface thereof, near the upper section.

A table 16 is pivotally hinged to the hinge connection 14 in any preferred manner so that the table can be folded back against the exterior surface of the section 13, which in 65 turn is folded outward and downward against the exterior surface of the member 1 previously mentioned.

A second standard having a base member 17 is used, said base member being pivotally 70 hinged thereto as at 18, a foldable section 19, which in turn has pivoted to it as at 20 a second foldable section 21, these foldable sections being adapted to fold inward against each other as is clearly obvious in 75 Fig. 1 of the drawings. A flange locking support 22 is fastened to the inner surface of the section 21 at the upper edge thereof and is adapted to support the outer end of our table 16 and to be locked in said position by means of a pin 23 or other suitable 80 fastening device which projects from the under surface of table 16, and is adapted to seat in apertures running through our member 22.

To thoroughly brace our table 16 and to complete a rigid structure of our foldable section, when in open position we utilize the advantage of a brace member 24 which is pivoted as at 25 to the under portion of our 90 table and which has a hook or inturned portion 26, adapted to clamp into our foldable section 21 in any preferred manner to bind the same. We also use a second brace member 27 which is pivotally connected to the 95 under surface of our table 16, as at 28 and which is connected to the lug 15 previously described by a bolt, pin 29 or other suitable fastening device. When our device is in open position, table set to its assembled 100 place and braces clamp into their normal position, we get a very rigid and substantial device. For further convenience we can support a drawer 30 from the under side of our table 16 by means of right angle flanges 31 105 and 32.

Hingedly connected to the lower edge of our base section 17 is a foot device 33, said device being hinged to the section 17 as at 34, the device 33 having downturned foot 110 portions 35 and 36 as clearly shown in Fig. 5 of the drawings. Midway of our device

33 is a bearing support 37 adapted to seat the end of the shaft 9 when in operable position as can clearly be seen from one of the drawings.

5 Our treadle member which is mounted upon the shaft 9 as previously described is adapted to be folded up against the pitman 4. This is achieved by means of a collar member 38, as at 39, our shaft is pivoted to the 10 collar 38, by means of a pivot connection 40 which can clearly be perceived from Fig. 1 of the drawings. A sleeve or thimble 41 is adapted to slide over the collar 38, and lock the shaft and consequently the treadle into 15 open position when in use. The sleeve or thimble 41 is locked for this purpose by bolts 42 or other suitable device.

Section 1 previously described has a plurality of foot sections 43 and 44 which correspond to the foot sections 35 and 36 previously described, and our table 16 has an aperture 45 therethrough adapted to receive and lock a hand operated sewing machine thereon by means of a thumb-screw or other 25 suitable fastening device (not shown).

In operation we release the sewing machine from the hole 45, release our brace members 24 and 27, throw our table 16 over against the outer surface of the member 13, 30 and then fold said member 13 down against the member 1, thereby bringing the table 16 between section 13 and the member 1. We next take and release our thimble 41, 35 slide it back over the collar 38, and lift our shaft and treadle until it is in a vertical position thereby striking the pitman 4. We next fold the section 21 against the inner surface of the section 19, and in turn fold the sec-

tion 19 against the inner surface of our base member 17, thereby bringing the section 21 40 between the section 19 and the base member 17. We then fold our section 33 upward and bring our folded standard as now described in against the treadle, thereby having a compact and convenient portable device. 45

Having now described our invention and showing the operation thereof, what we desire to claim by Letters Patent is:—

A device of the character described, comprising a standard base having an upper hinged section adapted to fold outwardly thereon, a table hinged to said upper section adapted to fold outwardly thereon so that when said upper hinged section is folded outwardly said table will rest between said base and said upper hinged section, driving means arranged upon said base, actuating means pivotally mounted to actuate the same, a second standard base having upper hinged sections, connected to said actuating means, said second mentioned base adapted to be positioned against said first mentioned base when folded, and said table adapted to be fastened to said second mentioned base when in open position, and bracing means mounted between said table and both of said standard bases when in open position. 55

In testimony whereof we have signed our names to this specification in the presence of 60 two subscribing witnesses.

MARY McCABE.

WILLIAM J. McCABE.
